UNITED STATES PATENT OFFICE.

IRVIN A. WILLIAMS AND CHARLES I. WILLIAMS, OF UTICA, NEW YORK.

LOCOMOTIVE HEAD-LIGHT.

SPECIFICATION forming part of Letters Patent No. 365,112, dated June 21, 1887.

Application filed June 3, 1886. Serial No. 204,003. (No model.)

To all whom it may concern:

Be it known that we, IRVIN A. WILLIAMS and CHARLES I. WILLIAMS, citizens of the United States, residing at Utica, in the county 5 of Oneida and State of New York, have invented certain new and useful Improvements in Locomotive Head-Lights; and we do hereby declare the following to be a full, clear, and exact description of the invention, such as will 10 enable others skilled in the art to which it appertains to make and use the same.

Our invention consists in certain constructions and combinations of parts in a locomotive head-light, as will be hereinafter described, 15 and pointed out in the claims, whereby such head-lights are greatly improved for giving signals and indications to engineers or trainmen.

In the accompanying drawings, Figure 1 is 20 a perspective view of our improved signaling and indicating head-light with a portion of the reflector and burner-case broken away, so as to show a front top signal or indicator, an auxiliary reflector, and curtain, as employed by us. Fig. 2 is a vertical central section of a head-light similar to that shown in Fig. 1, but modified in construction by having a bottom signal and auxiliary reflector added to it. Fig. 3 is a vertical section showing the head-light, Fig. 1, modified by having the curtain placed outside of the reflector and burner-case. Fig. 4 is a front view of the head-light shown in Fig. 1, modified by having front side signals or indicators applied to it, the numbers 35 of said signals being placed in either vertical or horizontal lines, as shown by full black lines and by dotted lines. Fig. 5 is a horizontal section of Fig. 4. Fig. 6 is a vertical section of the head-light with the curtain removed. Fig. 7 is a front view of the curtain and cords for operating it and a portion of the reflector and burner-case in vertical section.

A in the drawings, Figs. 1, 2, 3, 4, and 6, is the reflector and burner-case; B, the main reflector; C, the burner; D, an ordinary side signal or indicator; E, a top front signal or indicator; F, an auxiliary reflector; G, a curtain; and H, a chamber in which the front signal or indicator, E, may be placed.

The signal or indicator chamber is placed 50 on the outside of the reflector and burner-case and in communication with said case, and the

signal or indicator is set therein forward of the main reflector and outside of the front of the main reflector. The signal or indicating 55 chamber serves the purpose not only of holding the signals or indicators, but may be made to serve for receiving and concentrating and reflecting the light from the burner and main reflector upon the signals or indicators, this 60 latter result being effected by giving a proper reflecting shape, as shown, to the back or top of the chamber, and constructing the inside surface of the chamber either of some bright reflecting material or painting said surface 65 white, the latter mode serving substantially the same purpose as the bright-surfaced material.

The auxiliary reflector F is used for reflecting the light received from the main reflector 70 B and burner C on the reflecting-surface of the signal or indicator chamber and therefrom on the signal or indicator, and is made of the form shown, or of any other suitable shape, and it is fastened on the inside of the case, 75 partly in front of the main reflector, overlapping it to a small extent, so as to catch upon its surface a portion of the main reflector and burner light, which is then cast on the surface of the signal or indicator chamber and therefrom upon the signal. The auxiliary reflector thus overlapping the main reflector to take the light for the signal or indicator, is a very important feature of our invention in connection with other parts, as by this construction 80 a small portion of the main reflector's light is utilized for this purpose, and we save the necessity of an extra reflector and burner to cast light on the auxiliary reflector and signal or indicator. 90

The curtain G is used to shut off the light from the head-light, and by preference it is fastened inside of the reflector and burner-case A, in front of the main reflector B and burner C and behind the large front glass, I, as shown 95 in Figs. 1 and 2; but, if desired, it can be placed outside of the case over the large front glass, I, as shown in Fig. 3.

The obscuring of the light from the head-light indicates to an engineer of an approaching train that the main track, which is a single track, is clean. The train, with its head-light obscured, is run on a side track, so as to allow the train on the main track to pass. As the

engineer of the approaching train passes the one on the side track, he sees the front top signal or indicator, E, which indicates to him what locomotive and train he is passing. The 5 light from the head-light being shut off from view by the curtain, it does not interfere with the light on the said signal or indicator, nor obscure it, but makes it more brilliant to be seen by the engineers or train-men.

10 This use of the curtain, in combination with a front signal or indicator and with a signal-chamber and auxiliary reflector, is a very important feature of our invention; and while we are aware that a curtain for shutting off the 15 light of a head-light is not new, we believe such a curtain has never been used in connection with an auxiliary reflector and a front signal or indicator which designates perfectly to engineers or train-men the number or name of 20 a locomotive they are passing. When the curtain is placed inside of the reflector and burner-case, it is shielded and protected, while raised from the reflector and burner heat by the auxiliary reflector.

25 The curtain may be arranged on a roller, J, either outside or inside the case A, and lowered by two cords, a' a', connected to lower end of the curtain and passed under pulleys a² a³, and then united as a single cord, a⁴, having a 30 pull-ring, a⁵, at its terminus, as shown in Fig. 8. By this arrangement the curtain can be lowered by a sidewise pull on the cord a⁴. Other methods of lowering the curtain may be adopted; but this arrangement is a very convenient one for a head-light. For raising the 35 curtain, an ordinary spring within the roller may be adopted; or crank-handles, or other known means, may be applied to the ends of the roller for that purpose.

40 The curtain may be made of an opaque material, so as to shut off the light of the head-light at the glass I completely; or it may be made of a translucent material, so as to show transparent as well as dim, or in a measure 45 obscure the light. The translucent curtain may be of a red, green, or any color which will show the color under the action of the light behind it in the night, and also be visible by reason of the color in the day when the light 50 is out.

By having the curtain colored, as described, it can of itself be used as a signal opposite the glass I and forward of the main reflector and burner, while the signal or indicator E is also 55 used for its special purpose.

In the different views of the drawings we have illustrated how our combination of front signal or indicator, signal or indicator chamber, and auxiliary reflector, and also the same in 60 combination with the curtain, can be employed either at the top, bottom, or front sides of the

reflector and burner-case, and also how it may be used in connection with a side signal or indicator, D, and light catcher or shield K on the longitudinal side of the reflector and 65 burner-case, and with an ordinary rear reflector, K', upon which light is cast by the burner through an opening, K², in the back of the main reflector, and therefrom reflected under the shield K upon the side signal, D; and we 70 desire to be protected in any and all of these ways and relations of using our invention on a locomotive head-light.

What we claim as our invention is—

1. The combination, with a locomotive head-light, of a reflector-case, a main reflector, a burner, a front signal or indicator chamber located forward of the main reflector, having a reflecting-surface, and an auxiliary reflector placed forward of the main reflector, said parts 80 being constructed and arranged substantially as described and shown, the auxiliary reflector being placed so as to slightly overlap the front of the main reflector and in rear of the large front glass, there being a clear open space between the 85 front edge of the main reflector and the front side of the reflector-case, with which said signal-chamber communicates, the arrangement being such that the burner-light is exposed directly to the signal, while the auxiliary reflector, in conjunction with the reflecting-surface of the signal-chamber and main reflector, throws light upon said signal, substantially as described and shown.

2. The combination, with a locomotive head-light, of a curtain, a reflector-case, a main reflector, a burner, a front signal or indicator chamber located forward of the main reflector, having a reflecting-surface, and an auxiliary reflector placed forward of the main reflector, 95 said parts being constructed and arranged substantially as described and shown, the auxiliary reflector being placed so as to slightly overlap the front of the main reflector and in rear of the large front glass, there being a clear 100 open space between the front edge of the main reflector and the front side of the reflector-case, with which said signal-chamber communicates, the arrangement being such that the burner-light is exposed directly to the signal, while the auxiliary reflector, in conjunction with the reflecting-surface of the signal-chamber and main reflector, throws light upon said signal, substantially as described and shown.

In testimony whereof we affix our signatures 115 in presence of two witnesses.

IRVIN A. WILLIAMS.
CHARLES I. WILLIAMS.
